UNITED STATES PATENT OFFICE.

CHARLES W. LUMMIS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

HEATING-FURNACE.

1,279,889.

Specification of Letters Patent. Patented Sept. 24, 1918.

Application filed April 27, 1914. Serial No. 834,580.

To all whom it may concern:

Be it known that I, CHARLES W. LUMMIS, a citizen of the United States, residing at Worcester, in the county of Worcester and 5 Commonwealth of Massachusetts, have invented a new and useful Improvement in Heating-Furnaces, of which the following, taken in connection with the accompanying drawings, is a specification.

10 The present invention relates to a furnace, of the regenerative type, particularly adapted for the heating of a continuous row of billets or metal bars, and also adaptable for the heating of other classes of articles, as 15 will hereinafter appear. It is an object of the present invention to provide a furnace in which the products of combustion travel across the hearth and lengthwise of the billets progressively advancing there- 20 through, rather than lengthwise of said hearth, as is the case in the ordinary type of continuous furnace. A further object resides in the provision of a preheating chamber for the billets to be heated, into 25 which they are introduced prior to their entrance into the main heating chamber of the furnace. A still further object contemplates the provision of means for controlling the quantity of hot gases passing 30 transversely across the main hearth, in order to adapt the furnace to the heating of billets of varying sizes and temperature requirements.

The above objects, as well as others appearing hereinafter are accomplished by 35 the construction and arrangement of parts as hereinafter described, and pointed out in the annexed claims.

In the accompanying drawings, 40 Figure 1 is a view in horizontal section, taken through the heating chamber of a furnace constructed in accordance with my invention.

Fig. 2 is a vertical longitudinal sectional view of the furnace.

Fig. 3 is a vertical cross sectional view on line 3—3, Fig. 1.

Fig. 4 is a fragmentary view similar to Fig. 3, illustrating a modified construction.

50 Fig. 5 is a view similar to Fig. 2, showing the said modified construction in longitudinal section.

Like reference characters are used to denote like parts in the several figures.

Referring to the drawings, 1 denotes the 55 furnace, which contains a heating chamber 2, formed between an arched roof 3 and a sloping floor 4. The billets or bars to be heated are introduced at doors 5, provided in the side walls of the furnace near its 60 rear end, onto the floor of the heating chamber, which may be provided with a suitable track, if desired, for the support of the billets. The billets, each of which extends transversely of the furnace, are progressively advanced toward the forward end of the chamber 2 by pushers 6, and are discharged through doors 7, provided in the side walls at the forward end of the furnace.

The furnace herein disclosed is designed 70 for the use of producer gas and is of the regenerative type. To this end, duplicate sets of regenerative passages are provided, which are alternately used for the admission of the combustible and air to form the 75 fuel charge which is admitted to the heating chamber, and for the passage of the products of combustion from said chamber to the stack.

Referring particularly to Fig. 3, there is 80 shown a pair of gas passages 8, 8' extending longitudinally of the furnace along each side, and a pair of passages 9, 9', each of the, latter adapted to furnish air to the combustible supplied by the interior adjacent gas 85 passage. The passages 8, 8' and 9, 9' extend practically throughout the length of the furnace; each is provided with checkerwork as is usual in furnaces of this type; and each is provided with means adapted to communicate with the forward portion of the heating chamber 2. Each gas passage 8, 8' has a series of spaced ports 12 leading upwardly therefrom and communicating with a longitudinal channel 13 extending along the side 95 wall of the furnace and opening into the heating chamber 2. Each air passage 9, 9' has a series of spaced ports 14 leading to its respective channel 13 in alternating relation to the ports 12 leading from the adjacent 100 gas passage.

At the rear end of the furnace the passages 8, 8' and 9, 9' are suitably connected to reversing valves 10, 10 in the manner ordinary in furnaces of the regenerative type. 105 In one position of such valves, the gas passage 8 on one side of the furnace supplies the fuel charge, the adjacent air passage 9

providing for the admission of air to support the combustion of the same. In this position of the reversing valves the combustible and air forming the fuel charge are admitted from the ports 12 and 14 along one side of the heating chamber, passing from the corresponding channel 13 transversely across said chamber and entering the passages 8' and 9' by means of which are led the products of their combustion through said reversing valves to the stack 11. In the other position of the valves 10, the combustible and the air are led to the heating chamber through the passages 8' and 9', passing transversely across the chamber and discharging into the stack 11 through the passages 8 and 9. The specific means and the arrangement of passages for effecting this reversal of flow of the flame form no part of the present invention, the same being well known to those skilled in the art to which this invention appertains.

The channels 13, above referred to, extend from the forward end of the furnace rearwardly of the heating chamber 2 to an intermediate point in the length thereof. The products of combustion pass transversely across that portion of the heating chamber which is traversed by said channels 13, the said portion constituting the main heating chamber 15 of the furnace. The rear portion of the heating chamber 2 is heated by the heat radiated from the forward portion thereof, and forms in effect a preheating chamber 16 in which is maintained a lower temperature than in the chamber 15. The billets are introduced into the preheating chamber 16 and are gradually pushed forward into the main heating chamber 15 where they are brought up to the desired temperature. The preheating chamber 16 is provided with openings 17, which communicate with flues 18 leading to the stack 11. By this means a relatively small portion of the products of combustion which would otherwise pass transversely across the main heating chamber 15 are drawn rearwardly and longitudinally thereof to supply heat to the preheating chamber 16.

Each gas port 12 is adapted to be opened and closed by a sliding damper 19, carried in the side wall of the furnace adjacent said port. Each air port 14 is likewise adapted to be opened and closed by a sliding damper 20, the dampers 20 being arranged in alternating relation to the several dampers 19 on the same side of the furnace. This control of the combustion ports makes it possible to shut off partially or entirely any desired number of either kind of ports, whereby the intensity of the heating may be readily controlled, and furthermore, the area over which the flame is effective may be limited to any desired portion of the length of the main heating chamber 15.

The means disclosed for limiting the active area of the heating chamber 15 are highly desirable when the character of the work to be heated is subject to variation. For instance, in heating large billets, all of the dampers 19 and 20 would be opened to get the full heating effect of the furnace, while on smaller work, a portion of the dampers 19 and 20 would be closed in order to avoid danger of overheating.

In Figs. 4 and 5 I have illustrated an alternative construction for the main heating chamber of the furnace, which involves the provision of arched partitions 21 depending from the roof of the heating chamber, and extending transversely of said chamber, whereby to divide the same into substantially separate and independent heating chambers or passageways 22. The walls 21 depend in close proximity to the floor 4, space being left to provide for the passage of a billet thereunder. Each wall 21 is provided with a pipe 23 extending longitudinally thereof for the passage of cooling water. The provision of the walls 21 makes it possible, if desired, to concentrate the heat in the main heating chamber at a particular point or points, by the opening of the dampers 19 and 20 associated with one or more of said chambers 22.

Although I have shown means for introducing and withdrawing the work through doors in the side walls at the rear and front ends respectively of the heating chamber, I do not wish to be limited to this particular manner of introducing the work. It will be apparent that the work can be introduced and withdrawn through doors located in the end walls of the furnace, if desired.

In a furnace of the above described character, it is possible to vary the character of the work introduced without waiting for the furnace to be emptied of work of a given character. For example, work requiring a great amount of heat may be passing through the furnace. If it is desired to follow this work with work requiring a lesser amount of heat, the latter may be introduced immediately, and upon the entrance of the second batch of work into the main heating chamber 15, a portion of the dampers 19 and 20, all of which have been wide open for the work immediately preceding, are closed to prevent the overheating of the work entering the chamber.

An important feature of the present invention resides in the passage of the flame parallel to the length of the billets as they pass through the furnace, together with the provision of means for reversing the direction of travel of the flame at will. The uniform heating of the billets throughout their entire length is thereby insured, and furthermore, by the shifting of the reversing valves 10, 10, the deposits of tar and soot

- which would clog the passages 8 or 9 when continuously used as exhaust passages, become cleared by the passage therethrough of fresh gas and air.
- 5 Furthermore, it will be apparent that work of a different character from the billets which are progressively advanced through the heating chamber can be heated within the above described furnace. To this end
- 10 I have provided doors 24 in the front end wall of the furnace, adapted for both the introduction and withdrawal of articles to be heated within the main heating chamber 15.
- The operation of my furnace on the re-
- 15 generative principle not only contributes to the efficiency with which the billets are heated, but also promotes the rapid change in the temperature within the main heating chamber 15, when such a change is desired.
- 20 This is due to the fact that the working temperature of this portion of the furnace is considerably lower than the maximum obtainable temperature.
- I claim,
- 25 1. In a heating furnace, a heating chamber, a plurality of partitions carried by the walls of said heating chamber to divide the same into a plurality of similar passageways, each partition being spaced above the
- 30 floor of said chamber, means for advancing a row of billets through said chamber transversely of said passageways, and means for directing products of combustion through said chamber longitudinally of said pas-
- 35 sageways.
2. In a heating furnace, a heating chamber, means for dividing said heating chamber into a plurality of passageways lying wholly above the floor of said chamber,
- 40 means for admitting products of combustion to each of said passageways at one end thereof, means for exhausting said products from the other ends of said passageways and means for advancing a row of billets
- 45 transversely of said passageways.
3. In a heating furnace, a heating chamber, a plurality of depending partitions carried within said heating chamber, each partition terminating short of the floor of said chamber, means for advancing a row of billets through said chamber beneath said partitions, and means for directing products of combustion through said chamber longitudinally of the billets of said row.
4. In a heating furnace, a heating chamber, a plurality of depending partitions carried within said chamber, each partition being spaced above the floor of said chamber, means for advancing a row of billets through said chamber beneath said partitions, and means for directing products of combustion through said chamber across said row of billets.
5. In a heating furnace, a heating chamber, means for advancing a row of billets through said chamber, a plurality of partitions carried within said chamber to form passageways above said billets, means for directing products of combustion through said passageways, and means for drawing a portion of said products of combustion through the heating chamber transversely to said passageways.
6. In a heating furnace, a heating chamber, a plurality of partitions depending from the roof of said chamber and spaced from the floor thereof, means for directing products of combustion through said chamber longitudinally of said partitions, means for advancing a row of billets through said chamber beneath said partitions, and means for drawing products of combustion transversely of said partitions beneath the lower edges thereof.

Dated this 23rd day of April, 1914.

CHARLES W. LUMMIS.
